UNITED STATES PATENT OFFICE.

WILLIAM U. FAIRBAIRN, OF HYDE PARK, MASSACHUSETTS.

STEAM-BOILER SETTING.

SPECIFICATION forming part of Letters Patent No. 380,197, dated March 27, 1888.

Application filed March 14, 1887. Serial No. 230,818. (No model.)

To all whom it may concern:

Be it known that I, WILLIAM U. FAIRBAIRN, of Hyde Park, in the county of Norfolk and State of Massachusetts, a citizen of the United States, have invented a new and useful Improvement in Steam-Boiler Setting, of which the following is a full, clear, and exact description, reference being had to the accompanying drawings, forming a part of this specification, in explaining its nature.

This improvement is designed to secure the most perfect combustion of combustibles employed to heat steam-boilers and to utilize as much as possible of the heat generated.

15 It consists in the arrangement in front of the flue in which the boiler is set of a combustion-chamber in which the fuel is distilled into combustible gases, and interposing between such chamber and the flue beneath the boiler 20 a bridge-wall perforated by two converging channels for the products of combustion, which channels are inclined upward and inward, so that the gases passing through them shall interfere before they strike the shell of the 25 boiler.

In the drawings, Figure 1 is a vertical longitudinal section which exposes the boiler in elevation and the combustion-chamber and its duct as if the cut were made along one of the 30 lines x x or y y of Fig. 4. Fig. 2 is a transverse vertical section along the broken line z z z z of Fig. 1, whereby a view is given of the uptake, the flue-sheet, the center of the roof of the combustion-chamber, and the end of the combustion-chamber. Fig. 3 is an end elevation of the exterior of the front of the boiler-setting. Fig. 4 is a sectional plan of the roof of the combustion-chamber, taken through the air-tubes.

35 Like letters represent like parts in all the figures.

A is the boiler. It is set with a large flue, B, under it. The flame returns through tubes, which are shown at C in Fig. 2, and is carried 45 away by the uptake D, which leads to the stack. In front of this boiler is the usual boiler-front with doors, as shown at E, Fig. 3. A large fire-box, F, Fig. 1, is built in front of this boiler, and it has a roof the top of which 50 about coincides with the bottom of the boiler. A thick and heavy bridge-wall, G, is interposed between this fire-box F and the flue B

beneath the boiler. Through this bridge-wall pass channels or ducts f, leading from the combustion-chamber of the fire-box F into the flue B, and these channels are marked in Fig. 1 f, and are directed upward, as shown in Fig. 1, and inward, as shown by dotted lines in Fig. 4. As they open into the flue B at about the same level and point upward at about the same angle and inward upon converging angles, it will be seen that the products of combustion, when they pass into the flue B, will enter upon two lines which converge laterally and coincide in their upward direction. 65

Through the roof of the combustion-chamber are made sinuous channels g, the delivery ends of which converge, so that the current of air to support combustion will interfere with the current of combustible gas, and by the interference of these gaseous currents make a thorough mixture of the air to support combustion with the combustible gases, and both of them being at high temperatures the combustion will be very perfect, the more so because these interfering currents will cause the gyratory movement of the gases in the flue B, which is considered so important to secure perfect combustion, with a minimum admission of air, that the fan-blower is frequently recommended for 80 use, even at the expense of considerable power, in order to produce this effect. 75

To control the admission of air according to the necessities of combustion, a register, h, is applied to the induction-orifice of each of the air-tubes, g, and this register may be automatically controlled by the heat of the furnace by placing in the furnace - roof, as shown at Fig. 4, a metallic rod, i, with a tapering end. This rod is held at its proper position by having its abutment firmly fixed in the brick-work of the boiler, and the lengthening and shortening of this rod will cause its conical end to protrude more or less, the protrusion of the end of the rod serving to give lateral movement to a system of levers and links shown in Fig. 5, in which the movement of the rod i longitudinally causes the power end of the lever k to be displaced laterally, and hence to communicate motion to the link e, and through that to the handle m of the register h, thus causing it to revolve upon its center and admit more or less air to the tubes g, as may be desired. 95 100

The fire-box F may be fed either through the fire-door at the side marked *n*, Fig. 1, or through a fire-door in the top; and when using wood, chips, tan, or the like it will probably be better to feed through the top.

I am aware of Patent No. 310,582, to Gulickson, and No. 271,989, to Ritchie, both of which show two passages in the bridge-wall connecting the furnace with a flue beyond; but neither of these passages are inclined positively in an upward and inward direction, so that the gases of combustion are deflected by said passages and caused to come together or unite in front of the bridge-wall and below the lowermost point of the boiler. Neither do these patents describe any connection with flues in a bridge-wall which direct the gases of combustion from the furnace to a common concentrating-point immediately in front of the bridge-wall, with air-inlets arranged to supply air to these gases at their said converging-point, or immediately in front of the bridge-wall, and I therefore consider that they do not contain the essential elements of my invention.

Having thus fully described my invention, I claim and desire to secure by Letters Patent of the United States—

1. The combination, with the main flue B of a boiler-setting, of the fire-box F, by means of the upwardly-directed converging channels *f* through the bridge-wall, substantially as described.

2. The combination of the main flue B of a boiler-setting with a fire-box placed in front thereof, with the upwardly-directed and converging flues *f*, and the air-channels *g*, substantially as described.

3. The combination, in a boiler-setting of a fire-box, F, placed in front of and below the body of the boiler A, and provided with a bridge-wall, G, separating the main flue B of the boiler-setting from the fire-box F, which bridge-wall G is perforated by the upwardly-

directed and converging flues *f*, substantially as described.

4. The combination of the boiler A with the fire-box F, located below the body of the boiler and in front of the flue-sheet thereof, and the main flue B of the setting, which said fire-box F is separated from the flue B by a bridge-wall, G, through which bridge-wall G the upwardly-inclined and converging passages *f* are made, substantially as described.

5. The combination of the boiler A with its setting, which setting contains the flue B, and the fire-box F, situated in front of and below the body of the boiler and in front of the flue B, and connected with said flue B by upwardly-inclined and converging passages *f*, and the air-channels *g* in the roof or walls of said fire-box, substantially as described.

6. In a boiler-setting, the combination of a fire-box, F, the bridge-wall G, separating the main flue B of the boiler-setting from the fire-box F, the upwardly-directed converging flues *f*, the air-channels *g*, the bevel-ended thermostatic rod *i*, the register *h*, and the system of levers and links *k l m*, substantially as described.

7. The combination of the converging air-channels *g* with the converging and upwardly-directed gas-channels *f* and the fire-box F and main flue B, all being contained in and surrounded by the boiler-setting, substantially as described.

8. The boiler-setting containing the main flue B, the fire-box F, the upwardly-directed and converging flues *f*, and the converging air-channels *g*, all substantially as and for the purposes described.

WILLIAM U. FAIRBAIRN.
